UNITED STATES PATENT OFFICE.

JOHN F. O'CONNOR, OF CHICAGO, ILLINOIS, ASSIGNOR TO WILLIAM H. MINER, OF CHICAGO, ILLINOIS.

DRAFT-RIGGING FOR RAILWAY-CARS.

1,136,041.

Specification of Letters Patent.

Patented Apr. 20, 1915.

Application filed April 25, 1914. Serial No. 834,290.

To all whom it may concern:

Be it known that I, JOHN F. O'CONNOR, a citizen of the United States, residing at Chicago, in the county of Cook and State of Illinois, have invented a certain new and useful Improvement in Draft-Rigging for Railway-Cars, of which the following is a full, clear, concise, and exact description, reference being had to the accompanying drawings, forming a part of this specification.

My invention relates to improvements in draft rigging for railway cars.

The object of my invention is, to provide a draft rigging for railway cars in which buffing and pulling shocks are distributed over a wide area of the draft members.

In the drawings forming a part of this specification, Figure 1 is a vertical longitudinal section of a draft rigging embodying my invention, and showing the parts in normal position; Fig. 2 is a plan view, partly in horizontal section, on line 2—2 of Fig. 1, showing the parts in their position in full buff; Fig. 3 is a cross section taken on line 3—3 of Fig. 1; Fig. 4 is a cross section taken on line 4—4 of Fig. 1; Fig. 5 is a perspective view of one of the followers.

Referring to the drawings, the numerals 6—6 indicate draft members, or parts of the car-frame to which the draft rigging is applied, 7 an upper stop member, and 8 a lower stop member. The stop members are preferably channel-shaped, the lower stop member preferably having its flanges 9—9 up-turned, and the upper stop-members 7 preferably having its flanges 10—10 down-turned. The stop members 7 and 8 are vertically spaced apart and are secured to the draft members 6—6 preferably by the rivets 11—11 passing through the flanges of the stop members and adjacent portions of the draft members. The stop members are provided with forward vertical slots 12—12 forming front stop shoulders 13—13 and front limiting stop shoulders 14—14 in the stop members. The stop members are also rearwardly provided with vertical slots 15—15 forming rear stop shoulders 16—16 and rear limiting stop shoulders 17—17 in the stop members. A draft gear 18 is mounted between the draft members, the draft gear preferably comprising a shell 19 having friction elements 20 and spring elements 21 therein. The friction elements 29 prefer-

ably comprise a plurality of friction shoes, preferably 3, indicated by the numerals 22—22, a wedge 23, and anti-friction rollers 24, there being one roller interposed between each friction shoe and the adjacent face of the wedge 23. The spring elements 21 preferably comprise an outer spring 25 and an inner spring 26 nested therein, the springs being forwardly seated against the friction shoes, and rearwardly seated against the friction shell. A connecting bolt 27 connects the wedge 23 to the shell, the connecting bolt having a head 28 received in a forwardly opening recess 29 in the wedge 23, and a nut 30 received in the rearwardly opening recess 31 provided in the rear end of the shell. The draft gear is engaged at its forward end by a front follower 32, and at its rearward end by the rear follower 33, the said followers being hereinafter more particularly described. A draw-bar 34, only the rear end thereof being shown in the drawing, is provided with a transverse slot 35 to receive the coupler key 36, which extends laterally through transverse slots 37—37 provided in the forward ends of the draft links 38—38, the coupler key being received at its ends in slots 39—39 in adjacent portions of the draft members 6. The slots 39—39 are longitudinally extended to permit forward and rearward movement of the coupler key 36 therein, and the slots 37 in the draft links 38 are rearwardly extended to permit the rearward travel of the key 36 therein on rearward movement of the draw-bar without buffing strain upon the coupler key. Near their rear ends, the draft links 38 are provided with transverse slots 40—40 adapted for the passage of the rear key 41, which with the draft links 38 forms a draft yoke, the ends of the key 41 being received in slots 42—42 in adjacent portions of the draft members 6, the slots 42—42 being forwardly extended to permit the forward movement of the key 41 therein. The followers 32 and 33 are of similar construction, each comprising a plate 43, each plate being provided near its vertical edges with outwardly extended flanges 44—44. The flanges 44—44 of the front follower 32 are forwardly extended and spaced apart to receive the rear end of the draw-bar 34 between them, the front edges of the said flanges being provided with forwardly opening slots 45—45 adapted to receive the coupler key 36. The rear follower 33 is similarly constructed, the rear edges of the flanges 44—44 being provided with forwardly opening slots 45—45 adapted to receive the coupler key 36.

pler key 36 therein, each flange being also provided with upper and lower stop shoulders 46—46 adapted to co-act with the front stop shoulders of the stop members. The 5 upper and lower ends of the front follower extend into the slots 12—12 in the upper and lower stop members, and on rearward movement of the draw-bar are adapted to engage against the front limiting stop shoulders 14—14 to limit the rearward movement 10 of the follower and prevent the solid compression of the compression resisting parts of the draft gear. The flanges 44—44 of the rear stop member 33 are rearwardly extended 15 and are provided with rearwardly opening slots 47—47 similar to the slots 45—45 in the front follower, and adapted to receive the rear key 41 therein. The flanges 44 of the rear follower are provided with 20 upper and lower stop shoulders 48—48 adapted to co-act with the rear stop shoulders 16—16 provided in the stop member. The upper and lower ends 49—49 of the rear stop member are received in the slots 15—15 25 in the stop members, the plate 43 of the rear follower 33 being adapted on extreme forward movement of the rear follower to engage against the rear limiting stop shoulders 17 to limit the compression of the compression resisting parts of the draft gear. 30

On rearward movement of the draw-bar, the coupler key 36 moves rearwardly in the slots 37 of the draft links 38 without buffing strain upon the coupler key 36, the draw-bar 35 forces the front follower rearwardly, compressing the compression resisting elements of the draft gear, the shell of the draft gear being held against rearward movement by the rear follower 33, the rear follower being held against rearward movement through the engagement of its stop shoulders against the stop shoulders 16—16 of the stop members. The rear follower may also be held against rearward movement by the 40 rear key 41 engaging the rear follower in the rearwardly opening slots therein, the rear key 41 being held against rearward movement through its engagement against the rear ends of the slots 42—42 in the draft 45 members by reason of the rearwardly extended flanges 44 of the rear follower 33. The rear stop shoulders 16 are rearwardly spaced apart from the rear end of the draft gear, lengthening the area of engagement 50 between the stop members and the draft members, more widely distributing the buffing shock to the draft members, and distributing the shearing stress upon the means for connecting the stop members to the draft 55 members, the said means consisting preferably of the rivets 11—11. The buffing movement of the gear is limited by the engagement of the front follower 32 against the front limiting stop shoulders 14—14, the 60 area of distribution of the shock to the draft 65 members

members following this engagement on full compression being widely distributed rearwardly, and being forwardly distributed by means of the comparatively lengthy forward extension of the stop members made possible by reason of the forwardly extended flanges 44—44 of the front follower. The slots 39—39 in the draft members may be rearwardly terminated at a point adapted to stop the rearward movement of the coupler key 36 simultaneously with the engagement of the front follower against the front limiting stop shoulders 14—14 of the stop members. 70 75

On forward movement of the draw-bar, 80 the coupler key 36, engaging the forward ends of the slots 37 in the draft links 38, draws the draft links forwardly, the draft links in turn drawing the rear key 41 forwardly in the slots 42—42 in the draft members, the said key forwardly actuating the rear follower 33, which in turn forwardly actuates the draft gear, the draft gear being stopped at its forward end by the front follower 32, the stop shoulders 46—46 of the front follower engaging against the front stop shoulders 13—13 of the stop members. On complete forward movement, the rear follower engages against the rear limiting stop shoulders 17—17 of the stop members, 90 thus limiting the compression of the draft gear. The slots 42—42 in the draft members may be forwardly terminated at a point to stop the forward movement of the rear key 41 simultaneously with the engagement 95 of the rear follower 33 against the rear limiting stop shoulders 17. In forward movement of the draw-bar and in full compression of the draft gear, the shocks of the draft rigging are widely distributed to the 100 draft members in a manner similar to that hereinbefore described in connection with the buffing movement of the draft rigging. It will be observed that the engagement of the followers, through their flanges, with 105 the connecting keys for the draft links holds the followers against accidental downward displacement. 110

I claim:

1. In a draft rigging for railway cars, in 115 combination, a draft yoke having a cross connecting member and a follower having longitudinally extending flanges, the flanges of said follower being provided with outwardly opening slots to receive the cross connecting member of the yoke. 120

2. In a draft rigging for railway cars, in 125 combination, draft members, upper and lower stop members secured thereto, a draw bar, a draft yoke connected to the draw-bar, a draft gear mounted between the draft members, followers for the ends of the draft gear, the draft yoke comprising draft links and front and rear keys connecting said links, each follower having longitudinally 130

extending flanges provided with outwardly opening slots to receive a key, the stop members having vertical openings to receive the upper and lower ends of the followers, the 5 ends of said openings forming stop shoulders, the followers having shoulders coacting therewith.

3. In a railway draft rigging, the combination with draft members, upper and lower 10 stop members secured to the draft members, said stop members being provided with slots near the ends thereof, a draw-bar, a draft yoke and a draft gear, of followers at the ends of the draft gear, each follower having 15 longitudinally extended flanges notched at their upper and lower ends to thereby form shoulders coöperating with said stop members.

4. In a draft rigging for railway cars, in combination, draft members, upper and lower stop members secured thereto, said stop members comprising substantially horizontal plates extending between and connected to the draft members and provided with slots intermediate their ends, a draw-bar, a draft yoke, a draft gear, and followers at the ends of the gear, each of said followers having longitudinally extending side flanges slidable between said upper and lower stop members, each of said followers 30 having also extended upper and lower ends extending into said slots.

JOHN F. O'CONNOR.
